US0D1080863S

(12) **United States Design Patent** (10) **Patent No.:** **US D1,080,863 S**
(45) **Date of Patent:** **** Jun. 24, 2025**

(54) **MEDICAL ADHESIVE APPLICATOR BODY**

(71) Applicant: **OKAPI MEDICAL, LLC**, Akron, OH (US)

(72) Inventors: **Darren Obrigkeit**, Aachen (DE); **Benjamin Reed Dewinter**, Cincinnati, OH (US); **Jack Goodman**, Ann Arbor, MI (US); **David Kay**, Akron, OH (US); **Christian Mackin**, Aliso Viejo, CA (US); **Jonathan Morgan**, Westlake, OH (US); **Ananth Murthy**, Akron, OH (US); **Daniela Höller Obrigkeit**, Aachen (DE); **Gary Pennington**, New Franklin, OH (US); **Joseph Spalding**, Elyria, OH (US); **Michael Tracz**, Brecksville, OH (US); **Paul Wyman**, Maastricht (NL)

(73) Assignee: **OKAPI MEDICAL, LLC**, Akron, OH (US)

(**) Term: **15 Years**

(21) Appl. No.: **29/837,213**

(22) Filed: **May 3, 2022**

(57) **CLAIM**

The ornamental design for a medical adhesive applicator body as shown and described.

DESCRIPTION

FIG. 1 is a front perspective view of a medical adhesive applicator body;

FIG. 2 is a top plan view thereof;

FIG. 3 is a first side view thereof;

FIG. 4 is a bottom plan view thereof;

FIG. 5 is a front end view thereof;

FIG. 6 is a rear end view thereof; and,

FIG. 7 is a second side view thereof.

The broken lines in the drawings depict portions of the medical adhesive applicator body that form no part of the claimed design.
